AMUSEMENT DEVICE

Application filed August 24, 1926. Serial No. 131,185.

This invention relates to improvements in amusement devices and has particular reference to a device for testing the skill of an operator and which may be used in connection with a game of chance.

An object of the invention resides in providing an amusement device wherein a suitable element adapted to be struck by the hand of the operator or with a suitable instrument is movably mounted on a supporting structure and adapted to operate an indicating mechanism for registering the operation of the element so that the indication may be used in determining the skill of the operator.

15 A further object of the invention resides in providing an amusement device having a movable element adapted for operation on a suitable support through the striking of the device by the operator having suitable indicating means operated thereby for registering the skill of the operator, which construction is mounted on a suitable support and interchangeable for operation either by right or left hand players.

20 The invention further comprehends the provision of a structure of the above mentioned character in which a suitable base member is provided with means for mounting the movable element and the indicating mechanism in such relation that it may be removably associated with a suitable casing so as to enclose the device in said casing when not in use and to rigidly support the casing or in which the base member may be 25 reversed in the casing or removed therefrom when it is desired to play a game.

The invention comprehends numerous other objects and improvements residing in the details of construction and arrangement 30 of the parts which are more particularly pointed out in the following detailed description and in the claims directed to the preferred form of the invention, it being understood, however, that various changes in the size, shape and relation of the parts may be made for carrying out the invention which are clearly within the scope and spirit of the invention as herein set forth.

35 In the drawings forming part of this application:—

Figure 1 is a side elevation of the device showing the parts in housed relation and a portion of the housing broken away to show a portion of the mechanism therein.

Figure 2 is a plan view of the base member showing in full and dotted lines the two positions of the game device thereon.

Figure 3 is a vertical sectional view taken on the line 3—3 of Figure 2.

Figure 4 is a vertical sectional view taken on line 4—4 of Figure 1.

Figure 5 is an enlarged plan view of the game device showing portions broken away and adapted to particularly illustrate the relation of the operating arm and the indicating hand in their normal positions.

Figure 6 is a sectional view taken on the line 6—6 of Figure 5.

Figure 7 is an end elevation of the indicator.

Figure 8 is a detail view showing how the base member and the casing are assembled so that the hook members will secure the base member in the position shown in Figure 1.

A suitable supporting plate is indicated at 1 which is preferably of elongated rectangular form having its portion recessed as indicated at 2 to receive the free edge portion of the casing member 3. The free edge portions of opposite sides of this casing member are formed with slotted portions at 4 to receive the eyes 5 mounted on the plate member 1, while the hooks 6 on opposite sides of the casing 3 in the position of the parts as shown in Figure 8 are adapted to have the end portions 7 extend through the eyes 5 for rigidly retaining the casing and the supporting plate in assembled relation to house the device as shown in Figure 1.

A suitable base member 8 is attached to the supporting plate 1 by the pivot screw 9 more particularly shown in Figure 3 for movement so that the base may be positioned in either of the two positions shown in Figure 2 in full and dotted lines, respectively. In order to retain this base member in either of these positions the same is provided at 10 with a socket receiving the pressed metal housing 11 which carries the resiliently projected automatic catch member 12. This

catch member is adapted to cooperate with the opening in the latch plates 13 mounted in the supporting plate 1 in spaced relation and in position so that they are aligned with the center portion of the supporting plate member 1 and at opposite sides of the pivot screw 9 in order that the automatic catch member when engaged therein will hold the base member 8 in the full line or the dotted line positions shown in Figure 2. The two positions of the base member are to permit operation of the device either by a right or left hand operator, respectively, as will be hereinafter more clearly explained.

The central portion of the base member 8 is provided with an opening at 14 therethrough which is closed by the bearing plates 15 secured to the opposite sides of the base member as clearly shown in Figure 3. Said plates are formed with aligned bearings for rotatably mounting the shaft 16 having reduced extensions provided with bearing engagement in said bearing plates, one of said extensions indicated at 17 extending beyond the upper bearing plate as shown in Figure 3 and mounting the operating arm 18 on the free end portion thereof in spaced relation with the face of the base member 8. A coil spring 19 is mounted on the shaft 16 and has one end anchored in the shaft and the opposite end anchored in one of said bearing plates and normally serves to rotate the operating arm 18 in one direction, said arm being limited in its movement by the removable stop pin 20 mounted in the free edge portion of the base 8.

Interposed between the operating member 18 and the adjacent bearing plate 15 is the indicating pointer 21 rotatably mounted about the shaft extension 17. This indicator or pointer 21 is more particularly shown in Figures 5 to 7 inclusive and includes a hub portion 22 having an annular and laterally extending flange from one side of the center portion thereof as indicated at 23 surrounding the opening which receives the reduced extension 17 on the shaft 16. The periphery of the hub portion 22 is provided with a plurality of laterally projecting curved fingers 24 which form resilient friction elements and are projected from the flange 23 of the opposite side from pointer 21 so as to frictionally engage the bearing plate 15. The moment arm for the force of friction for elements 24 is greater than for element 23 so that the friction between 23 and 18 during the counter-clockwise movement of arm 18 will not be sufficient to move the pointer back. In order that the pointer 21 will operate with the rotation of the arm in one direction, a projection 25 is provided intermediate the ends of the pointer extending upwardly and into the path of movement of said arm 18 so that as it rotates in the direction of the arrow shown in Figure 5 the

pointer will be moved with the arm 18 to the extent of its arc of rotation where it will remain due to the increased friction between the bearing plate in the pointer as above explained so that the return movement of the arm 18 under the influence of the spring 19 will not affect the position of the pointer 21.

A suitable arcuate strip 26 is applied to the face of the base member 8 in concentric relation to the shaft 16 and under the pointer with which it cooperates to indicate the extent of the movement of the arm 18. The free end of the arm 18 is provided with an extension 27 on which is mounted a preferably resilient or yieldable body 28 forming an impact member adapted to receive a blow of a stick or other instrument as well as operation by the hand to produce sufficient impact for operating the pointer to register the result of such impact on the scale 26.

With the device constructed as above described in which the operating arm 18 receives an impact adapted to operate the arm in one direction only and the parts are positioned as in Figures 2 and 5 and the operating arm 18 pointing in the direction toward the operator that a right handed operation will be required to produce an impact with the body 28 for moving the operating arm 18 in the direction of the arrow. Should a left handed operator desire to operate the device the handle 29 is grasped with the hand and the entire base member 8 rotated on its pivot screw 9 until the catch 12 seats in the latch plate 13 at the left hand side of Figure 2 so that the base member will be in the dotted line position as shown in Figure 2. In this position the left hand operator may hit the body 28 so as to operate the arm in the same direction to produce an indication on scale 26 as when used by a right hand operator. For a left hand operator the arm 18 points away from the operator.

In operating the device the impact on the body 28 may be provided by hitting the body with the hand or through the use of a handle or stick similar to a golf club in order that the impact will be sufficient to rotate the arm and the shaft 16 against the tension of the spring 19, and in which rotation the pointer 21 will be moved to indicate the extent of rotation of the arm 18 as a result of the impact applied to the body 28. In this way an amusement device is provided in which success in operating the device is dependent upon the skill of the operator so that it may be used as a chance device depending upon such skill of the operator to determine the result in a predetermined chance arrangement through the operation of the arm 18. The results are attained by reading the position of the pointer on scale 26. Should it be desired to change the tension on the spring 19 it will be understood that the stop member 20 may be removed and the arm rotated in

one direction one or more times to either increase or decrease the tension on the arm 18. The stop member is then replaced after the desired tension on the operation of the arm 5 18 is obtained.

The plate member 1 provides a suitable holding means for the device to prevent its movement in operation so that the operator may suitably hold the supporting plate 10 against moving when operating the arm 18 by hitting the member 28. It is to be understood, however, that if desired, the base member 8 may be suitably mounted on a permanent support rather than the plate member 1. 15 It is to be further noted that the plate member 1 effectively receives the casing 3 which provides the container structure for the device including the member 28 with the parts as shown in Figure 1 so that the device 20 may be conveniently shipped or mailed without danger of injuring any portion of the mechanism. Through the recessed construction of the supporting plate 1 as indicated at 1 and the reception of the free edge portion of 25 the casing 3 therein it will be understood that the assembled casing and supporting plate form a rigid enclosure in cooperation for the device.

This construction provides a novel chance 30 or game device for amusement purposes at carnivals and the like and also for indoor use.

By properly graduating the scale 26 and using a suitable chart or picture of a golf course a game may be played indoors to simulate golf while numerous other results having considerable advantage and amusement may be obtained with the use of the device above described.

Having thus described the invention, what 40 we claim as new and desire to secure by Letters Patent is:—

1. An amusement device, comprising a base member, an indicating mechanism, an arm for operating said indicating mechanism 45 having one end pivotally connected to said base, stop means limiting the movement of said arm, resilient means for normally retaining said arm engaged with said stop means under tension, said arm adapted to receive an impact, said indicating mechanism 50 registering the deflection of said arm away from said stop means under said impact, and said stop means being removable from the base to allow reverse operation of the arm to 55 change the tension of said resilient means.

2. An amusement device, comprising a base member having an opening therein, a shaft in said opening having extensions on opposite ends thereof, a pair of bearing plates 60 mounted on the base for rotatably receiving said extensions, an arm having one end secured to one of said extensions and movable over the base, a resilient member attached to said shaft and one of the bearing plates for 65 normally rotating said shaft and arm in one

direction, means on the base for engaging said arm and limiting its movement, said means retaining said resilient member under tension and operable to release the arm for rotation to change said tension, and indicating means for registering the deflection of the arm in a direction away from said limiting means by an impact with the free end thereof, said bearing plates serving to maintain said shaft, resilient means and arm in assembled relation on the base member. 70

3. A golf device of the class described, comprising a supporting plate, a base member pivotally mounted on said supporting plate, means for releasably locking said base member in either right or left hand playing positions on said supporting plate, and a golf game device having means operably rotatable in one direction mounted on said base member. 75

4. An amusement device, comprising a supporting plate, a game device operable in one direction, and means mounting said game device at one end of said supporting plate operable to permit the positioning of said game device in either of two positions on said supporting plate, said game device being operable by a right-handed operator when set in one of said positions, and by a left-handed operator in the other of said positions, the operator in either case being at the end of said supporting plate opposite to that at which the game device is mounted. 80

5. An amusement device, comprising a base member having an opening therein, bearing plates mounted on opposite sides of said base member and over said opening, a shaft extending through said opening and rotatable in said bearing plates, an operating arm having one end mounted on one end of said shaft, 85 said arm being in spaced and substantially parallel relation to said base member, a resilient member having one end attached to said shaft and the opposite end to one of said bearing plates for rotating said shaft and arm in one direction, a stop pin removably mounted in said base member for engaging said operating arm and limiting the rotation thereof with said shaft, said resilient member normally retaining said arm against said stop pin under tension, and a pointer rotatable on said shaft between said operating arm and base member having frictional contact with one of said bearing plates sufficient to retain the pointer in any set position on 90 said base member, said pointer having means engaged by said arm for rotating said pointer by the movement of said arm. 95

6. An amusement device, comprising a base member, a shaft rotatable therein, an operating arm mounted on said shaft for rotation therewith, said arm being substantially parallel to said base member, resilient means tending to rotate said arm in one direction, a stop on said base for engaging said arm and 100

against which said arm is normally held under tension of the resilient means, and a pointer formed of an elongated strip having one end rotatably mounted on said shaft between said base member and operating arm, said strip having a plurality of fingers formed thereon adjacent said shaft and engaging said base member, said fingers normally engaging said base member with sufficient friction to prevent rotation of said pointer during rotation of said shaft, and a projection on said pointer with which said operating arm engages for rotating said pointer by said arm under predetermined conditions.
